DESIGN FOR A DISTRIBUTOR COIL ADAPTER

Victor W. Thomas, Waukegan, Ill.

Application July 19, 1943, Serial No. 110,709

Term of patent 14 years

(Cl. D26—1)

To all whom it may concern:

Be it known that I, Victor W. Thomas, a citizen of the United States and resident of Waukegan, in the county of Lake and State of Illinois, have invented a new, original, and ornamental Design for a Distributor Coil Adapter, of which the following is a specification, reference being had to the accompanying drawing, forming a part thereof.

In the drawing,

Fig. 1 is a perspective view of the outer or exposed side of the distributor coil adapter showing my design; and

Fig. 2 is a perspective view of the bottom or under side of the adapter.

I claim:

The ornamental design for a distributor coil adapter, as shown.

VICTOR W. THOMAS.
